MACHINE FOR PLUCKING HAIR FROM FUR SKINS

Louis S. Eisen, Newark, N. J.

Application December 21, 1954, Serial No. 476,807

2 Claims. (Cl. 69—26)

The present invention is directed to a machine which is adapted to pluck hair from fur skins and to leave the actual fur, thus improving the quality thereof.

It has been customary to accomplish the plucking of the hair by hand operations, which were quite complicated and difficult. It was necessary to soak the skin in a suitable solution, removing water by an extractor and then drumming the skin with sawdust. Thereafter the wet skin was folded with the fur outside and placed in a drying room to remove the water from the fur but not from the hide itself. The skin was then chalked to prevent slipping of a hand knife; the skin was secured to a block and the operator ran the knife with heavy pressure over the fur.

There were a number of disadvantages inherent in this operation in that a great amount of dust was produced which caused discomfort to the operator and was a health hazard. The work involved was quite heavy and often the operators did a slipshod job. In the operation the hide itself was damaged and part of the skin was lost. Also, a very substantial amount of the fur was torn out and this often reached from 30% to 40%, thus reducing the quality of the finished fur. Such operations required approximately two days.

The present invention is intended and adapted to overcome the difficulties and disadvantages inherent in the removal of hair from fur skins, it being among the objects of the present invention to avoid the necessity of any pre-treatment of the skin, to reduce the time necessary for the operation, to avoid the necessity of burdensome work by the operator and to provide a substantially automatic operation.

It is also among the objects of the present invention to provide a machine which is simple in construction, effective in operation and which is capable of removing hair from fur skins without damage or loss.

It is further among the objects of the present invention to provide a machine which may be readily operated by relatively unskilled workers and in which such operation results in highly efficient removal of hair without any substantial removal of fur.

The invention is more fully described in connection with the accompanying drawings constituting a part hereof in which like reference characters indicate like parts, and in which—

Fig. 1 is a front elevational view of a machine for the stated purpose and made in accordance with the present invention;

Fig. 2 is a side elevational view thereof;

Fig. 3 is a top plan view thereof;

Fig. 4 is an enlarged vertical cross-sectional view of the upper portion of the machine showing particularly the means for removing the hair;

Fig. 5 is a diagrammatic view showing the various driving connections for the elements of the machine;

Fig. 6 is a perspective view of a plate which assists in the de-hairing operation and

Fig. 7 is an enlarged fragmentary vertical cross-sec-

2

tional view showing the relationship of the knife and roll arrangement.

The machine includes a frame 1 having a cylinder 2 mounted on a shaft 3 in suitable bearings. A pulley 4 on shaft 3 connects by belt 5 to pulley 6, which in turn is connected to a gear reduction 7. A pulley 8 on gear reduction 7 is connected by belt 9 to pulley 10 on the shaft of the driving motor 11. Cylinder 2 is usually perforated as shown at 12.

10 Drum or cylinder 2 is provided with a longitudinal slot 13. A lever arm 14 is mounted on shaft 15 and has a tooth 16 adapted to fit into recess 17 of fixed bar 18. Lever arm 14 has a cam follower 19 adapted to contact with cam 20 on shaft 3 and a spring 21 tends to maintain 15 contact between the cam and follower.

A rubber roller 22 at the top of drum 2 cooperates with spiral knife 23. A pair of lateral guides 24 are intended to permit the vertical movement of box 24' within which roller 22 and knife 23 are held. A screw 25 at the top 20 of said box operates in a fixed nut 26 on the frame of the machine and provides means for adjusting the vertical position of box 24'. A hand wheel 27 permits such adjustment. Support 28 also assists in guiding box 24'.

A plate 29, as more particularly shown in Fig. 6, has 25 sets of openings 30 for a pair of hinges 31 secured at 32 to support 28. Said plate has openings 33 for holding rod 34 carrying spiral spring 35, whereby limited pivotal movement of plate 29 is provided, depending upon the thickness of the skin being treated. The forward end 30 of plate 29 has openings 37 adapted to retain the bearings for feed roll 38. A brush 39 is mounted in front of feed roll 38. As shown in Fig. 4, the skin 40 travels to the right, due to the rotation of drum 2.

Holder 41 on which roller 22 is mounted operates 35 horizontally in recess 42. Set screws 43 threaded in the frame at 44 bear against block 41 and are adapted to adjust the distance between roller 22 and knife 23.

In an opening at the rear of box 24' is a funnel 45 connected to duct 46—46' connected to a suction blower 47. 40 On pulley 48 attached to the shaft of motor 11 is a belt 49 connected to pulley 50 fixed on the main shaft 51 in the rear of the machine. A pulley 52 is connected by belt 53 to pulley 54 of blower 47.

On said shaft 51 is a pulley 55 connected by belt 56 to 45 pulley 57 on shaft 58. Said shaft is journaled in frame 1 and is connected to knife 23 through a universal joint 58'.

In the front of the machine is an apron 59 held on the 50 frame by brackets 60. In the back of drum 2 is a chute 61, the upper end of which is secured to the top of frame 1 and the lower end 63 of which is secured at the front of the frame and below drum 2. Thereby a treated skin falls along the chute and is delivered in the front of the machine.

55 In the operation of the machine, a skin 40 is placed on apron 59 and motor 11 is started causing revolving of drum or cylinder 2. When slot 13 approaches the apron, arm 14 is raised off of bar or jaw 18 by the action of cam 20 and the operator inserts the end of the skin between jaw 18 and jaw 18' mounted on arm 14, after which said jaws close and grip the skin. As shown in Fig. 4, brush 39 raises the hair of the skin when then passes under feed roll 38 and under rubber roller 22 and spiral knife 23. The hair enters opening 29' of plate 29 and is gripped between roller 22 and knife 23 which pulls out the hair without injury to the skin. Blower 47 pulls air through box 24', funnel 45 and out of the system, carrying the hair along in the air stream.

After the skin has been de-haired, cam 20 releases the jaws and the skin drops into chute 61, being delivered at the front of the machine beneath the apron where it is within reach of the operator. No preliminary treatment

of the skin is necessary and raw skins may be de-haired in the machine. Very little physical effort is required on the part of the operator; there is no dust present and no health hazard. The operation is rapid and the skins are undamaged. Even though the operator is relatively unskilled, he is capable of effectively treating the skins as the operation of the machine is practically automatic. Various adjustments may be made to suit the particular skins being treated.

I claim:

1. Hair plucking machine comprising a frame, a rotatable drum in said frame, cooperating roller and rotatable knife mounted on said frame adjacent to the surface of said drum, means for feeding a fur skin between said drum and roller and knife, and means adjacent to the surface of said drum for gripping said skin, a plate mounted on said frame between said drum and said roller and knife, said plate having an opening to permit entrance of said hair from below, and an opening in the front of said plate in which a feed roll is rotatably mounted.

2. Hair plucking machine comprising a frame, a rotatable drum in said frame, cooperating roller and rotatable knife mounted on said frame adjacent to the surface of said drum, means for feeding a fur skin be-

tween said drum and roller and knife, and means adjacent to the surface of said drum for gripping said skin, a plate mounted on said frame between said drum and said roller and knife, said plate having an opening to permit entrance of said hair from below, and an opening in the front of said plate in which a feed roll is rotatably mounted, and a brush in front of said roll.
